UNITED STATES PATENT OFFICE.

JACOB C. RUBEL, OF EMMETSBURG, IOWA.

ADJUSTABLE WINDOW-SCREEN.

1,217,222.

Specification of Letters Patent. Patented Feb. 27, 1917.

Application filed December 23, 1914, Serial No. 878,655. Renewed July 26, 1916. Serial No. 111,333.

To all whom it may concern:

Be it known that I, JACOB C. RUBEL, a citizen of the United States, residing at Emmetsburg, in the county of Palo Alto, State 5 of Iowa, have invented certain new and useful Improvements in Adjustable Window-Screens; and I do hereby declare the following to be a full, clear, and exact description of the invention, such as will enable others 10 skilled in the art to which it appertains to make and use the same.

This invention relates to window screens and has special reference to a screen adjustable both for width and height so that it 15 may fit any window opening whether the sash be raised to its full extent or somewhat lowered.

The principal object of the invention is to improve and simplify the general construction 20 of devices of this character.

A second object of the invention is to provide a collapsible window screen wherein the members, which slide with reference to each other, may be constructed of tubular 25 metal.

With the above and other objects in view the invention consists in general of certain 30 novel details of construction and combination of parts hereinafter fully described, illustrated in the accompanying drawings, and specifically claimed.

In the accompanying drawings, like characters of reference indicate like parts in the several views, and:—

35 Figure 1 is a side elevation of a screen constructed in accordance with this invention.

Fig. 2 is a section on the line 2—2 of Fig. 1.

40 Fig. 3 is a section on the line 3—3 of Fig. 1.

Fig. 4 is a detail view of a portion of one 45 of the members showing the manner of slitting the same in order to form the completed member.

In carrying out the objects of the invention as disclosed in the present drawings there is provided a screen composed of four 50 separate corner sections 10, 11, 12 and 13. Two of these sections are made of tubular metal as indicated at 11 and 13 and the tube is so arranged as to be rectangular in general contour but certain portions thereof are

bent inward to provide oppositely disposed grooves 14 to receive coacting portions of 55 the adjoining members. The remaining members 10 and 12 are made of tubular metal but the metal is slit along a line 15 longitudinally of each branch and then split transversely as at 16 so as to provide two 60 tongues which are downwardly bent as at 17, said tongues constituting inturned edges on flange portions 18. It is to be noted that certain portions of the metal in the members 10 and 12 are left at the corner as at 19 so as 65 to support the parts in proper spaced relation. Each of the corner members or corner sash sections just described is provided with a separate piece of wire screen fabric as indicated at 20 and this fabric is free from all of 70 the sections except its own corner section so that the different pieces of fabric may slide, one on the other, when the screen is assembled. It is to be noted that the device when assembled is so arranged that the inturned 75 edges 17 enter the grooves 14 of the coacting members so that the two members can slide one on the other.

Now by this arrangement there is provided four corner screen sections which are 80 slidably interlocked and each of which has its own appropriate section of screen fabric so that the device may be enlarged, either sideways or vertically and thus be made to accommodate any size of window opening 85 within certain limits, these being from the size when totally collapsed to the size of the device when totally expanded in both directions.

There has thus been provided a simple 90 and efficient device of the kind described and of the character specified.

It will be obvious that many minor changes may be made in the form and construction of this invention without departing from the material principles thereof. It is not therefore desired to confine the invention to the exact form herein shown and described, but it is wished to include all such as come properly within the scope claimed. 95 100

Having thus described the invention, what is claimed as new, is:—

A collapsible screen comprising four rectangular sheets of screen fabric, an L-shaped section connected to the outer edges of each 105 sheet, a pair of said sections being rectan-

5 gular in cross section and having grooves formed upon opposite sides thereof, the other pair of sections being also rectangular in cross section and having inwardly directed tongues for slidably engaging the grooves of the other section.

In testimony whereof, I affix my signature, in the presence of two witnesses.

JAKE RUBEL.
